UNITED STATES PATENT OFFICE.

ALLEN H. DOW, OF WHARTON, PENNSYLVANIA.

PAINTING AND DECORATING TOOL.

Application filed May 24, 1927. Serial No. 193,854.

This invention relates to the art of painting and decorating surfaces and has for its object the provision of a tool or hand machine arranged and adapted for striping, 5 stenciling and straight surface painting, the tool or machine including a fluid reservoir and embodying novel paint feeding and applying means as well as novel and mechanical structural improvements and advan- 10 tages.

The modern trend in interior decoration toward the use of figured stencil and striping effects in borders and panels requires, in the absence of special tools, machines or ap- 15 pliances, a highly skilled painter-decorator and such work requires much care and time and is proportionately costly. The device or machine of the present invention not only makes it possible for the unskilled or amateur 20 to do this class of work, but greatly increases its production by the skilled painter, improves its quality and lowers its cost.

These and other features and advantages will be seen from the detailed specification 25 when read in connection with the accompanying drawings forming part thereof and in which:—

Figure 1 is a perspective view of a preferred embodiment of the invention arranged 30 for stenciling or striping work,

Figure 2 is a vertical longitudinal section through the device shown in Figure 1,

Figures 3 and 4 are vertical sections on the 35 lines 3—3 and 4—4 respectively of Figure 2,

Figure 5 is a perspective view of the device 40 illustrating the use of brushes instead of striping or stenciling bands,

Figure 6 is a transverse vertical section 45 through the cylindrical pulley showing the application thereto of a brush ring,

Figure 7 is a longitudinal section through the same pulley illustrating the use of a centrally located brush ring and showing the interior construction of the pulley, and

Figure 8 is a detailed view of one of the 50 brush carrying sleeves or rings.

Referring to the drawings by numerals, 1 indicates spaced side bars of a frame joined at its rear end by an integral cross bar 2 and 55 at its front end downwardly bent end provided with rearwardly extending bayonet slot bearings 3 and intermediate its front and rear ends with downwardly extending feet 4 in which are journalled gauge wheels 5 at opposite sides of the frame. The forward edges of the feet 4 at their upper ends or

points of junction with the side bars 1 are slotted transversely or rearwardly and then vertically downwardly to provide opposed 60 bearings 6.

To the rear bar 2 of the frame is secured by riveting, brazing or otherwise, the oppositely extending feet 7 of a handle 8 mounted with the feet having portions 9 projecting beyond the side bars 1 of the frame and drilled 65 to permit the ends of threaded adjusting rods 10 to extend therethrough and be engaged by appropriate means such as the butterfly or wing nuts 11. The forward ends of the adjusting rods 10 are rigidly connected with a 70 bearing plate 12 and slidably mounted upon the side bars 1 of the frame by means of bar embracing guide yokes 13 at their rear ends, the forward ends being laterally offset and longitudinally slotted to provide vertically 75 opposed bearings 14, one above and the other below the side bars 1.

The bearings 3, 6 and 14 are of the "open" type, the cylinders or pulleys journalled in these bearings being held therein by tension 80 in the cases of the front and rear bearings 3 and 14 and by tension and gravity in the case of intermediate bearings 6. Between the forward bearing brackets 3 is mounted a cylindrical pulley member 15, preferably rubber faced and serving as the "road wheel" of the device by which operating motion is transmitted to the other cylindrical pulley, hereinafter referred to, and through which the device is operated to stripe, stencil or brush. 85 The cylinder 15 is easily inserted in its bearing by means of its journalling shafts 15^a being inserted upwardly and then backwardly in the slots forming the bearings 3 and are held at the rear ends of the said slots by the tension exerted thereagainst by a broad belt 16 of suitable belting material connecting the front end cylindrical pulley 15 with a cylindrical pulley 17, preferably of metal and journalled in one of the bearings 14 of the 90 sliding bearing plate 12 at the rear end of the frame. An intermediate cylindrical pulley member 18, which, in the disclosed embodiment of the invention, is formed as a hollow cylinder providing a paint reservoir, is 95 mounted in the bearings 6 in the spaced feet 4 of the frame, its upper face, engaging, as shown, the under-side of the belt 16 and acting as an idler, the tension of this belt against the face of the under-lying pulley 18 serving 100 to retain it in its bearing.

The reservoir cylinder, designated gener-

ically at 18 may be used to transfer the contained paint or other liquid decorating material to the surface to be painted or decorated in a variety of ways, in each of which the 5 same basic construction is employed. This common feature of construction resides in the embodiment of a cylinder having a plurality of flow-openings therein and one or more paint distributing mediums mounted on 10 the cylinder in flow-receiving relation to these openings.

In the use of the device for stenciling and striping, the construction shown in Figure 3 is employed in which the ends of the cylinder 18 are closed by flanged cups 19 having a plurality of perforations 20 which align with the perforations 21 at the open ends of the cylinder 18, the cup 19 being turned to bring the opening 20 in register with the openings 21 when it is desired to feed the contained paint through opening 21 to the distributing medium formed by bands 22 of absorbent material seating over the outside of the cylinder 18 and covering the feed holes 21 therein. In the embodiment illustrated in Figures 1 to 4, the endless belt 16 carries on its outer face, which contacts with idler or reservoir pulley 18, a plurality of strips or endless belts 23 of absorbent material which 30 may represent broad and narrow strips or decorative figured borders. These strips are positioned on the belt 16 in alignment with the paint distributing bands 22 of the cylinder 18 and their operative faces are passed 35 over these bands and are coated thereby with the appropriate color which is to be applied. In the use of the device for stenciling where a light pressure is desirable, the ends of the cylinder 15 may carry rubber tires which 40 may take the form of bands over the ends of the roller, reducing the pressure which would be transmitted to a wall through the figures on the stenciling bands such as 23 in Figure 1.

The cylinder 18, as shown, is provided with 45 hubs 24, spacing the end cups 19 from the feet 4 of the frame, between which the cylinder is journaled. Appropriately formed spindles 25 extend from these hubs into the slots forming the bearing 6.

50 Instead of utilizing the absorbing bands 22 and belt carried strips 23, the paint may be applied in some instances by brushes such as the striping brushes shown in Figure 5, or the cylinder 18 may have circumferential 55 rows of perforations covered by brush carrying sleeves or rings seating over these perforations as shown in Fig. 7. It is also within the concept of this invention to embody two or more compartments in the intermediate cylinder 18 which will hold differently colored paints which in such event would cooperate with a plurality of pads such as the bands 23 of Figures 1 to 4. Returning to the disclosure in Figures 5 to 8, in which the cylinder 60 65 18 applies the paint through brushes

carried by the cylinder, this cylinder is provided with flanged end cups 26, the flanged portion 27 of which extends substantially beyond the periphery of the cylinder and has its edges preferably rubber cased forming 70 rubber tires as at 28. Hubs 29 space the flanges 27 and the feet 4 of the frame.

As seen in Figures 5 and 6 of the drawings, brush rings are provided adjacent to the opposite ends of the cylinder 18. One of these brush rings is shown in detail in Figure 8 and embodies a channeled ring 30 to which a plurality of clusters of bristles 31 are appropriately wired at their ends, paint feeding holes 32 being formed in the ring adjacent to the base of the bristle cluster. These clusters are extended substantially tangentially of the cylinder 18 and when brought in contact with the surface to be decorated will have a wiping stroke similar to that given by hand application. The rings will be positioned on the cylinder so that their feed openings 32 will align with similar feed openings 33 in the cylinder 18 (Figure 6). In Figure 7, I have shown a brush sleeve disposed centrally of the cylinder 18 as illustrative of the variety of uses and adaptations possible with this device. When the device is used as shown in Figure 5, clearance is afforded the brush bristles as they rotate by 95 utilizing narrow belts 34 at the ends of cylinders 15 and 17. These belts may pass over the upper face of the hubs 29 of cylinder 18 outside the flanged ends 27 or the brush cylinder may be rotated otherwise, as by frictional engagement of its tired flanges 28 with the floor or wall. In order to give added attraction for these belts, the end cylindrical pulley 15 may have its face provided with 100 raised gripping teeth 35 as shown in Figure 105 5.

In the use of the form of the invention shown in Figures 1 to 4, it will be obvious that the reservoir cylinder being filled and the roller belts and strips 23 being appropriately positioned, the end cups 19 will be rotated to permit paint to flow through to the absorbent rings 22 after which the operator rotates the road wheel to effect a discharge of the paint to the strips 23 and placing the wheels 5 upon the proper place on the wall or ceiling engages the front end pulley 15 or road wheel frictionally with the surface as the device is moved longitudinally thereof, the end pulley 15 and wheels 5 being 110 in contact with the surface at all times and the striping or stenciling being applied by the strips 23 to the surface as the front pulley 15 is rotated thereby. As before stated, in stenciling work end tires will be used on the pulley to relieve, to some extent, the pressure applied by the stenciling strips or bands 23. The provision of vertically opposed bearings 14 above and below the frame bars 1 115 120 125 130 enables the use of pulleys of various sizes 130

including intermediate pulleys of large and small reservoir capacity. In the event that it is desired to change or refill the reservoir cylinder, it is merely necessary to rotate the 5 wing nuts 11 to relieve the tension on the belt, whereupon the cylinder may rest in its bearings and be removed. This applies when either the broad guide belt 16 is used or when the narrow belts 34 are used in conjunction 10 with the cylinder 18 with the brush medium. Releasing the tension effected through the sliding plate 12 enables the rollers or cylinders to be easily lifted out, the front cylinder 15 practically falling out from its bearing when 15 the tension is released. From the foregoing description it will be evident that the invention is susceptible of application through a variety of uses. Therefore, I do not desire to be unduly limited in the scope of the invention as stated in the appended claims except as made necessary by the prior art or the specific statement of the claims.

I claim:

1. A decorating device of the character described having in combination, a frame, end pulleys mounted therein in different horizontal planes, a belt connecting said pulleys, an intermediate idler pulley engaging said belt, means for effecting relative longitudinal adjustment of the end pulleys to vary frictional contact between the belt and both end and intermediate pulleys, one of said pulleys being formed with a paint reservoir having openings therein to flow its contents to the exterior of the pulley, and a paint receiving and transferring element engaging the peripheral surface of the pulley in flow-receiving relation to said openings.

2. A decorating device of the character described having in combination, a frame, cylindrical end pulleys mounted therein in different horizontal planes, a belt connecting said pulleys, an intermediate cylindrical idler pulley engaging said belt, means for effecting relative longitudinal adjustment of the end pulleys to vary frictional contact between the belt and both end and intermediate pulleys, one of said pulleys being formed with a paint reservoir having openings therein to flow its contents to the exterior of the pulley, a paint receiving and transferring element engaging the peripheral surface of the pulley in flow-receiving relation to said openings, and supporting wheels for said frame, one of said pulleys being formed to engage the surface to be decorated as a road wheel effective to turn said belt and the other pulleys.

3. A decorating device of the character described having in combination, a frame, end pulleys mounted therein in different horizontal planes, a belt connecting said pulleys, an intermediate idler pulley engaging said belt, means for effecting relative longitudinal adjustment of the end pulleys to vary frictional contact between the belt and both end and intermediate pulleys, one of said pulleys being formed with a paint reservoir having openings therein to flow its contents to the exterior of the pulley, a paint receiving and transferring element engaging the peripheral surface of the pulley in flow-receiving relation to said openings, and an annular paint distributing element seated over said series of openings.

4. A decorating device of the character described having in combination, a frame, end pulleys mounted therein in different horizontal planes, a belt connecting said pulleys, an intermediate idler pulley engaging said belt, means for effecting relative longitudinal adjustment of the end pulleys to vary frictional contact between the belt and both end and intermediate pulleys and the tension of said belt, said means including a manually operable tensioning means cooperating with one of said end pulleys, said pulleys having bearings in said frame in which they are firmly held while said belt is tensioned and from which they are freely removable when tension is relaxed.

5. A decorating device of the character described having in combination, a frame, cylindrical end pulleys mounted therein for relative longitudinal belt-tensioning adjustment, one of said pulleys providing a road wheel, a belt connecting said pulleys for rotation, an intermediate cylindrical idler pulley mounted in the frame and engaged at one side of the belt, one of said pulleys being hollow and providing a reservoir for decorating fluid with a series of flow openings therein, and an annular fluid distributing element mounted thereon in flow receiving relation to said openings.

6. A decorating device of the character described having in combination, a frame, cylindrical end pulleys mounted therein in different horizontal planes, a belt connecting said pulleys for rotation, one of said pulleys being formed to provide a road wheel, means for effecting bodily adjustment of the other of said end pulleys in a direction to vary the tension of the connecting belt, and an intermediate cylindrical idler pulley engaging one side of said belt and having a hollow interior providing a paint reservoir, the cylinder being provided with a plurality of flow holes therein having a fluid distributing medium thereover.

7. A decorating device of the character described having in combination, a frame presenting a handle portion with spaced side bars extending therefrom, end pulleys rotatably mounted between said side bars at points adjacent to their opposite ends and in different horizontal planes, an intermediate cylindrical idler pulley, a belt connecting said end pulleys for rotation, one of said end pulleys being journaled between said side bars at one end, spaced longitudinally slidably bearing plates adjacent to the other end thereof in which the other of said end pulleys is mounted, and means for adjusting

said bearing plates longitudinally of the side bars to vary this tension of the pulley connecting belt against both end and intermediate pulleys.

- 5 8. A decorating device of the character described having in combination, a frame presenting a handle portion with spaced side bars extending therefrom, end pulleys rotatably mounted between said side bars at points 10 adjacent to their opposite ends, an intermediate cylindrical idler pulley, a belt connecting said end pulleys for rotation, one of said end pulleys being journaled between said side bars at one end, spaced longitudinally 15 slidably bearing plates adjacent to the other end thereof in which the other of said end pulleys is mounted, and means for adjusting said bearing plates longitudinally of the side bars to vary this tension of the pulley con-

necting belt against both end and intermediate pulleys, said bearing plates being provided with opposed bearings therein at points above and below the side bars whereby the position of the axis of the pulley and the belt engaged face of the idler may be varied. 20 25

9. In a device of the character described, a frame, front and rear end cylindrical pulleys and an intermediate idler cylindrical pulley mounted therein, a belt rotatably connecting said pulleys, said front end pulley constituting a road wheel, and another of said pulleys providing a cylindrical paint reservoir, and a plurality of paint applying brush elements, carried by said reservoir cylinder and extending in lines approximately tangential to 30 35 a circle concentric with the axis of rotation of said reservoir.

ALLEN H. DOW.
